ROTARY HOOK MECHANISM FOR SEWING MACHINES

Max L. Waterman, Fairfield, Conn., assignor to
The Singer Manufacturing Company, Elizabeth,
N. J., a corporation of New Jersey

Application April 9, 1932, Serial No. 604,133

16 Claims. (Cl. 112—181)

This invention relates to sewing machines and more particularly to lock-stitch sewing machines in which the loop-taker makes a plurality of revolutions during each stitch-forming cycle.

One of the objects of this invention is to improve the thread-handling conditions of lock-stitch sewing machines.

Another object of this invention is to improve the frame structure of the machine to facilitate assembly and lubrication of the machine mechanism.

With the above and other objects in view, as will hereinafter appear, the invention consists in the devices, combinations, and arrangements of parts hereinafter set forth and illustrated in the accompanying drawing of a preferred embodiment of the invention, from which the several features of the invention and the advantages attained thereby will be readily understood by those skilled in the art.

This invention will be understood by reference to the accompanying drawing in which:

Figure 1 is a front elevation, partly in section, of the bed and loop-taker actuating mechanism of a sewing machine embodying my invention.

Figure 2 is a section taken along the line 2—2 of Figure 1.

Figure 3 is a section taken along the line 3—3 of Figure 1.

In the embodiment of this invention selected for illustration, the machine is constructed with the usual bed-plate 1, gooseneck 2 rising therefrom, needle 3 reciprocable in a fixed path and presser-foot 4. Fixed to the under side of the bed-plate 1 by the cap-screws 5 is a trough-shaped casing or sub-frame 6 having suitable bearings 7 in which is journaled the loop-taker actuating shaft 8. The main shaft of the sewing machine (not shown) is connected, by the clip-belt 11, in driving relation with the belt-wheel 9, fixed to the loop-taker actuating shaft 8 by the set-screws 10. The shaft 8 receives one rotation for each rotation of the main shaft, and hence for each reciprocation of the needle.

Fixed to the shaft 8 is a disk 12 provided with a stud 13 which is connected by a link 14 to a corresponding stud 15 on the gear-wheel 16 which is fixed by the set-screws 18 to the short shaft 17 journaled in a suitable bearing 19 in the casing 6 and held in operative position by a collar 20 fixed to the shaft 17 by set-screws 21. The shafts 8 and 17, which are disposed in parallel relation, have their centers out of line or offset 55 relative to each other, thus causing the short

shaft 17 to be rotated by the shaft 8 at a variable or differential speed.

Formed in the casing 6 is a bearing 22 located above the short shaft 17. The loop-taker shaft 23 is journaled in the bearing 22, and has fixed to one end a gear 24 meshing with the gear 16. The ratio of the gears 16 and 24 is as 1 is to 2, the gear 24 and shaft 23 making two complete revolutions for each revolution of the gear 16 and shaft 17. Fixed to the shaft 23 at its other end 65 is the usual loop-taker 25 adapted to cooperate with the needle 3.

Journalized in the bearing 26 is a rock-shaft 27 having secured upon its rearward end by the set-screws 28 a bifurcated arm 29 which embraces 70 the actuating eccentric 30 fixed on the short shaft 17. Fixed to the forward end of the rock-shaft 27 by the screws 31 is a thread-case opening arm 32 which engages the usual lug 33 on the thread-case 34. By this means the rock-shaft 75 27 receives an oscillation for each rotation of the short shaft 17; consequently the thread-case opening arm 32 engages the lug 33 on the thread-case and opens a passage for the needle-thread loop to pass the thread-case rotation-restraining finger 35 once for each rotation of the shaft 8.

The machine, in the present instance, is provided with a four-motion lower feed-dog 36 which is actuated in the usual and well known manner. It is obvious that any of the well known 85 types of work-advancing feeds may be employed.

The rotary-hook in machines of the class herein described is usually given two complete rotations for each needle-reciprocation for proper cooperation with the other elements involved in 90 the handling of the thread. During its first rotation, the hook seizes and casts the needle-loop around the lower thread-mass, this occurring during the upward movement of the needle. The second rotation of the hook, which occurs during 95 the descent of the needle, is an idle one. It has long been known that there is not sufficient time between the point in the cycle in which the needle-thread loop has been "cast off" the hook and the point in which the needle re-enters the 100 work, for the take-up to function properly and the feed to advance the work. Attempts have been made to overcome this difficulty, as for instance, by imparting to the rotary-hook three rotations for each stitch-forming cycle. When 105 a machine having a hook of this type is operated at high speed, the speed of rotation of the hook is so excessive as to very materially increase wear and friction-induced heating of the parts. In order to overcome this difficulty, I have provided 110

means for imparting an accelerated rotation to the rotary-hook during the loop-seizing and "cast-off" part of the stitch-forming cycle and a retarded rotation during the take-up and work-feeding part of the cycle.

In the operation of the machine the shaft 8 is driven through one complete rotation at a uniform speed for each reciprocation of the needle or each stitch-forming cycle. Each rotation of the shaft 8 is communicated to the hook-shaft 23, by means of the described connections, to produce alternate accelerated and retarded rotations of the hook or loop-taker, the one to two ratio of the gears 16, 24, distributing the acceleration and retardation of the shaft 17 to two successive rotations of the shaft 23 for each needle-reciprocation. It will be obvious that the acceleration of the loop-taker 25 during the loop-seizing part of the cycle causes the needle-thread loop to be seized and "cast off" earlier in the cycle, thus giving more time for the take-up to set the stitch and the feed-dog to advance the work.

It will be observed that the loop-taker actuating mechanism is journaled in the trough-shaped casing 6, and that the loop-taker 25 together with its actuating mechanism and the casing 6 form a unitary structure which may be assembled at some distant point, and later, when the entire machine is assembled, be secured to the bed-plate 1 by the screws 5, thus greatly simplifying the assembling of the machine. It will also be observed that the casing 6, forming a support for the loop-taker 25 and its actuating means, is so constructed as to provide a gear housing to eliminate the noise of the gear-drive and variable motion connection and that it also provides a lubricant reservoir, as shown at 37 in Figure 3.

To lubricate the bearing of the shafts 23, 17, and 27 from above the bed-plate, a single lubricant conduit 37 is provided in the casing 6. The conduit 37 connects the three bearing bushings 22, 19 and 26 which are provided with lubricant-receiving apertures 22', 19' and 26' and lubricant by-passing grooves 22'', 19'' and 26'', respectively. The upper end of the conduit 37 has a funnel-shaped mouth 37' which communicates with the lubricant-aperture 38 in the bed-plate 1. The lubricant-aperture 38 is normally sealed by a spring-pressed ball 39 to prevent lint, dust and other foreign matter from entering the lubricant-conduit 37. Likewise, to lubricate the bearing for the forward end of the actuating shaft 8 from above the bed-plate the casing 6 is formed with a funnel-shaped opening 40 leading to an aperture 41 in the bearing bushing 7. Directly above the funnel-shaped opening 40 the bed-plate 1 is provided with a lubricant-aperture 42 which is normally sealed by the spring-pressed ball 43.

From the foregoing description considered in connection with the accompanying drawing, the construction, manner of operation and several advantages of my improved loop-taker actuating means will be clearly and fully understood. It is apparent that such a device has a wide variety of uses, and it will be understood that the form, construction and arrangement of the several elements employed may be varied. Therefore, the privilege is reserved of resorting to all such legitimate changes therein as may be fairly embodied within the spirit and scope of the appended claims.

Having thus set forth the nature of the invention, what I claim herein is:—

1. In a rotary hook sewing machine, in com-

bination, a loop-taker, and means for imparting to said loop-taker one accelerated and one retarded revolution during each stitch-forming cycle.

2. In a rotary hook sewing machine, in combination, an actuating shaft adapted to make one complete rotation during each stitch-forming cycle, a loop-taker shaft, and variable speed mechanism connecting said shafts for imparting a plurality of rotations to the loop-taker shaft for each rotation of said actuating shaft, said variable speed mechanism producing a speed acceleration in one rotation and a speed retardation in a succeeding rotation of said loop-taker shaft.

3. In a sewing machine, in combination, a needle reciprocable in a fixed path, a loop-taker, means for producing a plurality of revolutions of said loop-taker for each reciprocation of the needle and including means for imparting a differential movement to said loop-taker.

4. In a sewing machine, in combination, a reciprocatory needle, a loop-taker adapted to perform a plurality of revolutions for each needle-reciprocation, and means for imparting to the loop-taker relatively fast and slow complete successive rotations for each needle-reciprocation.

5. A sewing machine having in combination, a needle reciprocable in a fixed path, a loop-taker and means for imparting to said loop-taker a plurality of revolutions of different durations for each reciprocation of the needle.

6. A sewing machine having, in combination, a needle reciprocable in a fixed path, a loop-taker cooperating therewith, a loop-taker shaft, an actuating shaft making a single revolution for each needle-reciprocation, and means connecting said loop-taker shaft and said actuating shaft for imparting to said loop-taker shaft a plurality of revolutions of different durations for each needle-reciprocation.

7. A sewing machine having, in combination, a reciprocating needle, a loop-taker, a constant speed drive-shaft, and means connecting said drive-shaft to said loop-taker, said means including speed multiplying gearing and a variable motion driving connection between said drive-shaft and said gearing.

8. In a sewing machine having a frame including a bed-plate, a reciprocatory needle, a loop-taker cooperating with said needle in the formation of stitches, actuating mechanism for said loop-taker comprising a loop-taker actuating shaft, a loop-taker shaft, an intermediate shaft having its axis offset relative to the axis of said loop-taker actuating shaft, a crank-and-link connection between said actuating and intermediate shafts, and speed multiplying gearing connecting said intermediate shaft with said loop-taker shaft.

9. In a sewing machine, a frame including a bed-plate, a reciprocatory needle, a loop-taker cooperating with said needle in the formation of stitches, a loop-taker actuating shaft, a trough-shaped casing provided with spaced bearing journals for said actuating shaft, and means for detachably securing said casing to the under side of said bed-plate, whereby the looper mechanism may be assembled and applied to the sewing machine as a unit.

10. In a sewing machine having a frame including a bed-plate and a hollow standard rising therefrom, a reciprocatory needle, a loop-taker cooperating with said needle in the formation of stitches below said bed plate, actuating mecha-

- nism for said loop-taker below said bed-plate, and a member detachably secured to the lower face of said bed-plate having the entire loop-taker actuating mechanism below said bed-plate 5 journaled therein.
11. A sewing machine having a frame including a flat bed and a hollow standard rising therefrom, a reciprocatory needle, a loop-taker, loop-taker actuating means below said bed, a trough-shaped member 10 separate from said bed in which said loop-taker actuating means is mounted, said means including a shaft having an outboard extension below said hollow standard, and means extending downwardly through the hollow stand- 15 ard to drive said shaft, said trough-shaped member being detachably secured to and closed by the under side of said bed.
12. A sewing machine having a frame including a flat bed-plate and a standard rising therefrom, a reciprocating needle, a loop-taker below said bed-plate and cooperating with said needle in the formation of stitches, a loop-taker actuating shaft, a loop-taker shaft, gears connecting said shafts in driving relation, and a casing detach- 20 ably secured to the lower face of said bed-plate having longitudinally spaced bearing journals for said actuating shaft and providing a housing and lubricant reservoir for said gears.
13. A sewing machine having a frame includ- 25 ing a flat bed-plate and a standard rising therefrom, a reciprocatory needle, a loop-taker cooperating with said needle in the formation of stitches, loop-taker actuating mechanism comprising a loop-taker actuating shaft, a loop-taker shaft, an intermediate shaft offset relative to said loop-taker actuating shaft, a link connec- 30 tion between said actuating and intermediate shafts, gearing connecting said loop-taker shaft with said intermediate shaft, and a member de- 35 tachably secured to the underside of said bed-
- plate and supporting and enclosing said loop-taker actuating mechanism.
14. A sewing machine having a frame includ- 40 ing a bed-plate and a standard rising therefrom, a reciprocatory needle, a loop-taker below said bed-plate and cooperating with said needle in the formation of stitches, a loop-taker shaft, variable speed mechanism connecting said shafts in driving relation, and a casing detachably secured to the lower face of said bed-plate having spaced bearing journals for said shafts and providing a housing and lubricant-reservoir for said variable speed mechanism. 80
15. A sewing machine having a frame including a flat bed-plate and a standard rising therefrom, a reciprocating needle, a loop-taker below said bed-plate and cooperating with said needle in the formation of stitches, a shaft supporting member disposed below the bed-plate, a loop- 85 taker shaft, an intermediate shaft, and a bobbin-case opener shaft journaled in said member, and a single lubricant-conduit communicating with all of said shafts. 90
16. In a sewing machine, a frame including a bed-plate and a hollow standard rising therefrom, a reciprocating needle, a loop-taker co- 95 operating with said needle in the formation of stitches, loop-taker actuating mechanism, said mechanism including a shaft having an outboard extension below said hollow standard, a sub- 100 frame having spaced bearings in which the entire loop-taker actuating mechanism below said bed plate is journaled and means for detachably securing said sub-frame to the under side of said bed-plate, whereby the loop-taker actuating mechanism may be applied to the sewing machine as a unit. 105
